UNITED STATES PATENT OFFICE

NEIL SINCLAIR, OF OAKLAND, CALIFORNIA, ASSIGNOR TO RIP VAN WINKLE WALL BED COMPANY, INC., OF OAKLAND, CALIFORNIA, A CORPORATION OF CALIFORNIA

PORTABLE FOLDING BED

Original application filed April 14, 1924, Serial No. 706,241, now Patent No. 1,607,925. Divided and this application filed October 12, 1926. Serial No. 141,060.

This invention relates to folding beds of the portable type which may be rolled about the room, both when folded to an upright position as well as when extended, and the objects of the invention are to provide a simplified, durable construction for such a bed and a simplified means of securing a great spread of the rollers supporting the bed when the same is being outfolded to extended position for use.

I have shown a bed of this type in my copending application filed on April 14, 1924, under Serial #706,241, and issued as Patent No. 1,607,925, November 23, 1926, and the present application forms a division of said copending application in being drawn to the disclosure of Fig. 4 thereof.

In the drawings hereto Fig. 1 is a view corresponding to said Fig. 4 of the copending application and shows the bed folded to vertical position with dotted lines indicating its outfolded or horizontal position. Fig. 2 is a plan view of Fig. 1, with the foot end of the bed broken away.

The various parts of the drawings are designated with the same numerals as used on the figures of the copending case so as to clearly identify therewith, but include some numerals taken from Fig. 1 of said case where lacking in original Fig. 4.

The construction shows a bed provided with a supporting frame comprising a head frame portion 28 and rigid therewith the lower frame portion 29 carrying the main pivots 30 of the body portion 27 which is adapted to swing on pivots 30 from the vertical folded position 27 in full lines to the horizontal dotted position as extended for use.

A pair of castors 7 is provided for the head frame portion of the bed, and spaced forward thereof is another pair of castors 26 arranged so as to provide a rolling support for the bed. The forward pair of castors 26 are supported each on a movable base portion 21 which is given a parallel horizontal movement by the arm 22 pivoted at its lower end to the base portion 21 and swinging about the pivot 23 carried by the body portion of the bed and which arm is under the control of the lever 24 pivoted at

its upper end to the arm and at its lower end at 31 to the frame 29, and the link 25 pivoted at its upper end to said lever and at its lower end to the rear end of the movable base portion 21. The castor roller 26 swivels on the member 21, and as the body portion 27 is swung down from the full line position to the dotted position the roller 26 moves longitudinally of the bed away from the roller 7 from full line position to dotted position, thus increasing the area of the supporting base, or spread of the castors as the center of gravity of the structure is shifted due to the movement of the body portion 27.

A simple lowering of the bed thus spreads the front castors directly away from the rear castors and positions the front castors more toward the foot 2 of the bed while firmly angularly braced to the bed portion 27 and the frame 29.

With the angular arrangement of levers and links in the folded position shown in full lines the folded position is stabilized as there is no tendency for the castors 26 to slip forward. This is due to several factors including the narrow angles of the levers when folded and to the rearward pull on the bed portion 27 by reason of the springs and mattress normally carried by the bed and occupying the space between the body portion 27 and the head frame 28. The initial lowering movement of the bed 27 resulting more in a rearward thrust to rollers 7 rather than a forward thrust to rollers 26 and which ordinarily is prevented from taking place accidentally by the head of the bed being close to the wall of a room or closet.

It is of course understood that the bed portion 27 is to be equipped with springs and mattress, but these features contributing nothing to this invention, have been omitted from the drawings.

I claim:

1. A folding bed comprising a supporting frame, a vertically arranged head piece secured to said supporting frame, a bed portion pivoted near one end to said frame on a horizontal axis so as to swing from a vertical to a lowered horizontally extended position, floor castors on said frame, a system of arms

pivoted to said bed portion and to said frame, a floor castor carried by said system of arms spaced forwardly from and cooperating with said castors in supporting the frame 5 with said head piece vertical, and said system of arms adapted and arranged to move said castor along the floor directly toward the foot of the bed upon lowering said bed portion.

10 2. A folding bed comprising a supporting frame, a vertically arranged head piece secured to said supporting frame, a bed portion pivoted near one end to said frame on a horizontal axis so as to swing from a vertical to a lowered horizontally extended position, a pair of floor castors on said frame, a system of arms at opposite sides of the bed each pivoted to said bed portion and to said frame, a floor castor carried by each system 15 of arms spaced forwardly from said castors and at all times cooperating therewith in supporting the frame, said system of arms adapted and arranged to each move its castor along the floor longitudinally of the bed away from 20 said castors upon lowering of the bed portion, and also to maintain the swivelling axis of the castor in operative position.

25 3. A folding bed comprising a supporting frame, a head piece secured to said frame, a bed portion pivoted near one end to said frame on a horizontal axis so as to swing from a vertical to a lowered horizontal position, supporting castors on said frame, an additional castor at each side of the bed spaced forwardly from the first mentioned castors, a member on which the additional castor is mounted with its swivelling axis substantially vertical, and leverage means pivoted to said frame, bed portion, and member arranged and adapted for moving the additional castors along the floor away from the first mentioned castors upon lowering of the bed, and to maintain the swivelling axes of the additional castors substantially vertical.

40 4. A foldable bed of the character described, comprising a supporting frame, a bed frame pivoted adjacent one end to said supporting frame, a leg structure connected to said frames adjacent the pivotal point thereof and for movement relative thereto, and separate anti-friction supporting members for the supporting frame and for the leg structure arranged to maintain an engagement with a floor to provide the sole support for the supporting frame on the floor 45 and requiring mutual cooperation to hold said frame in stable equilibrium when the bed is in folded position.

5. A foldable bed of the character described, comprising a supporting frame having a single pair of spaced supporting rollers fixed thereto, a bed frame pivoted adjacent one end to said supporting frame, a leg pivoted adjacent one end to said bed frame adjacent the pivotal point of said frames and

provided with a roller at its other end arranged to rest upon the floor, and a link connecting said leg and supporting frame arranged to move said leg during the folding and unfolding of the bed to dispose the roller of the leg to cooperate with said first rollers to support said frames in all positions of the bed in the supporting frame.
